(57) **CLAIM**

The ornamental design for a disruptor, as shown and described.

DESCRIPTION

The invention described and claimed herein may be manufactured, used, and licensed by or for the U.S. Government for U.S. Government purposes.

FIG. 1 is a perspective view of a disruptor showing our new design, as seen from the front and side thereof;

FIG. 2 is a perspective view as seen from the rear and side thereof;

FIG. 3 is a front elevation view thereof;

FIG. 4 is a side elevation view thereof, the opposite side being a mirror image thereof; and,

FIG. 5 is a rear elevation view thereof.
